TORQUE VECTOR ANALYZER

Roger Dean Stephenson, 18 E. Drive,
Columbia, Mo. 65201

Filed Sept. 20, 1968, Ser. No. 13,641

Term of patent 14 years

Int. Cl. D10—08

U.S. Cl. D52—6

FIG. 1 is a perspective view of the torque vector analyzer showing my new design;

FIG. 2 is a top plan view;

FIG. 3 is a front elevational view of the device seen in FIG. 2; and

FIG. 4 is a bottom plan view of the device in FIG. 2.

I claim:

The ornamental design for a torque vector analyzer, as shown.
